TOY FIGURE

Alan S. Reynolds, Bournemouth, England, assignor to Wonkie International Inc., Woonsocket, R.I.

Filed Aug. 14, 1970, Ser. No. 24,485

Claims priority, application Great Britain Feb. 17, 1971

Term of patent 14 years

Int. Cl. D21—01

U.S. Cl. D34—4

FIG. 2

FIG. 1

FIG. 6

FIG. 5

FIG. 1 is a perspective view of a toy figure embodying my new design;

FIG. 2 is a front elevational view thereof;

FIG. 3 is a side elevational view, the opposite side being identical with the illustrated side;

FIG. 4 is a rear elevational view thereof;

FIG. 5 is a top plan view thereof; and

FIG. 6 is a bottom plan view thereof.

I claim:

The ornamental design for a toy figure, as shown and described.
